UNITED STATES PATENT OFFICE.

HARRY ZIMMERMAN, OF FREMONT, OHIO.

MULTIPLY-FABRIC BUFFER-SECTION MANUFACTURE.

Application filed June 4, 1924. Serial No. 717,910.

To all whom it may concern:

Be it known that I, HARRY ZIMMERMAN, a citizen of the United States of America, residing at Fremont, Sandusky County, 5 Ohio, have invented new and useful Multiply-Fabric Buffer-Section Manufacture, of which the following is a specification.

This invention relates to buffers or fabric wheels and their manufacture.

10 This invention has utility when incorporated in multi-ply fabric buffing wheels.

Referring to the drawings:

Fig. 1 is a plan view, with parts broken away, of a machine for carrying out features of the invention herein;

15 Fig. 2 is a view of a set of plies as preliminarily anchored or tacked;

Fig. 3 is a view of the set of plies of Fig. 2 after trimming has occurred and with 20 stitching thereof started;

Fig. 4 is a view of the finished buffer section with a perforation therethrough, and as assembled into a wheel, parts being broken away to show an intermediate im- 25 pregnated ply;

Fig. 5 is a side view of the wheel of Fig. 4, parts being broken away;

Fig. 6 is a view on an enlarged scale of 30 features of the automatic buff shifting device and thread cutting mechanism of Fig. 1;

Fig. 7 is a fragmentary view of the buff shifting device from the left of Fig. 6;

Fig. 8 is an enlarged view of the thread 35 cutter of Fig. 1;

Fig. 9 is a plan view of features of control of the cutter and shifter of the sections or sets of plies in the machine of Fig. 1;

40 Fig. 10 is a fragmentary plan view of an endless chain type of traveling table for continuous sewing of buff sections instead of a circular table of Fig. 1;

Fig. 11 is a view of a straight line trans- 45 versely sewed buff section as produced from the machine of Fig. 10 with the lines through the center;

Fig. 12 is a view similar to Fig. 11, but with the lines of stitching off center;

50 Fig. 13 is a plan view of the race or track for carrying buffer seats in effecting sewing similar to the endless vertical plane type of carrier of Fig. 10;

Fig. 14 is a fragmentary plan view of 55 the carrier and table wherein the seats are carried upon relatively movable arms in-

stead of upon a rigid wheel as shown in Fig. 1, thus permitting various sizes of buffs to be conveniently accommodated in the same structure as well as permitting a ready 60 change of adjustment by shifting between the axis of the arm carrier and the machine head to provide a different transverse stitching position for the respective buffs as through the center, slightly over, or slightly 65 short of the center, or such other arc stitching line as may be desired;

Fig. 15 shows a buff with intersecting stitches beyond the center; and

Fig. 16 shows the buff having a stitching 70 line just short of the center.

Motor 1 is shown as connected to drive sewing machine head 2 as well as connected for rotating pulley 3 from which extends belt 4 for rotating pulley 5 fast with stem 6 75 mounted for rotation in bearing 7 as a base. This stem 6 carries main table or rotating platform 8 about which may extend stationary platform 9. There is clearance region 10 adjacent the sewing head 2 between the platform 9 as a stationary table and the rotating table 8 for operation of the stitching mechanism of the sewing head 2. This table is provided with a plurality of seats 11 permitting mounting of the material to 85 be operated upon in an annular series on this table 8.

In practice, fabric sections 12 of polygonal or irregular form may be mounted with warp and woof threads of one ply 12 at 90 an angle to the warp and woof threads of the next and adjacent ply 13. These plies as arranged in a set may be anchored together by tacking or preliminary stitching 14. The periphery irregularity may be 95 trimmed to produce circular plies 15 to fit in the seats 11 of the table 8. The group or set of anchored plies as placed in the respective seats 11 may be so held by arm 16 normally thrown against the upper portion of the ply by spring 17.

The rate of rotation of the table 8 is such as to take stitch feeding strain off the stitching device of the sewing machine head 2, and hold assembled plies in the seat 11 105 against disturbance either by the stitching head, stationary table 9, or other disturbing influence.

As passing the stitching head 2, stitching 18 may be continuous directly from one 110 one set of plies 15 to the adjacent set of plies with such plies in proximity for practical

continuity of stitching. Carried by bracket means 19 from the base 7 is cam 20 beneath the table 8. This cam 20, as a buff or ply section has passed the sewing head 2, has increased radius portion 21 into which snaps roller 22 as actuated by spring 23 thereby snapping outwardly hook knife 24 over the thread of the stitching 18 between adjacent sets of buffs.

10 In the continuation of the travel of the table 8, away from the stitching head 2, this hook knife 24 is gradually drawn inward by the cam 20 to draw the thread of the stitching 18 against fixed knife 25 to effect severing of the stitching 18 between the adjacent sections of plies being sewed or assembled. Each knife 24 of the plurality of such knives as indicated in Fig. 1, is successively operated by cam 20 in each complete rotation of the table 8. Thus, one knife cuts the threads from the stitching line or lines as extending between adjacent assembled groupings of plies. The threads thus cut are the threads from the stitchings 25 as formed in the single rotation of the table 8 subsequent to the previous cutting action by such knife. Accordingly, as these sets of plies at once pass away from the stitching head 2, the continuous stitching line is 30 severed to render the sets independent.

When this cutting is completed there is effected an angular shifting of the respective sets of plies to present a different line for stitching when such sets of plies again 35 reach the sewing head 2. To this end, bracket 26 carried by the base 7 is provided with replaceable variable length friction block 27 as mounted in position by set screw 28. This bracket 26 also carries cam 29. 40 This cam 29 rides against roller 30 on depending arm 31 pivoted to the buff engaging holding arm 16. Accordingly, the cam 29 is effective for lifting the arm 16 clear of the partially stitched set of fabric plies, and 45 while such arm is so lifted, the friction block 27 engages the friction disc 32 for effecting the desired step or turning action of shaft 33 carrying pin wheel 34 coaxing through opening 35 to engage the under 50 side of the set of plies and as slightly out of radial position as to the table 8 urge the set of plies into the pocket 11 with a simultaneous progressing action upon such set of plies to give a degree of shifting 55 whether 3° or 10° or such other distance as may be found desirable for the particular type of buff being produced.

It is, accordingly, clear that in the operation of the machine of Fig. 1, the tacked 60 and trimmed sets of plies as introduced into the seats 11 are automatically cared for by a continuity of stitching for producing completely formed buffs with intersecting stitchings; that as the stitching is continuous from one buff section to a succeed-

ing buff section the thread may be cut and the ply shifted for the regular progress of the stitching in completing the buff section.

The radius of the table 8 will determine the number of seats 11 which may be used as 70 well as the arc line of the stitching 18. The greater the radius, the more nearly the stitching line will approach a straight direction.

A simple type of machine may be adopted 75 for straight line sewing as instanced in Fig. 10. Stationary table 36 is shown as having thereon seats 37 of a traveling table, which traveling seats 37 of the traveling table are actuated by endless chain 38. Stitching head 80 2 produces straight line of stitching 39 while pulley 3 and belt 4 as driving pulley 5 is connected through gearing 40 to actuate the conveyor 38. While herein there may be automatic cutting as well as shifting, it is 85 shown that the operator may cut the threads of the stitching 39 and take the section as stitched from the right end of the machine and replace it at the left end of the machine at the desired angular stitching for the succeeding stitching line 39 therethrough. Here as in Fig. 1, the capacity for stitching 90 rate of the head 2 may be continuous with such number of threads and needles to carry such threads as may be found desirable in 95 practice. In Fig. 1, shifting of the buffs as well as cutting may be manual. The straight line stitching 39 as shown in Fig. 10, may be directly through centrally of the buffs as shown in Fig. 11, or by relative 100 adjustments between the stitching head 2 and the conveyor or chain 38, such stitching may be to other desired extent off center as shown in Fig. 12.

Instead of the endless chain or conveyor 105 38 as operating in a vertical plane, an endless carrier 41 may operate in a horizontal plane as shown in Fig. 13. Herein it is not so desirable to have the operator remove the sets of buffs and replace to the opposite side 110 of the stitching head 2 for the continuous line or travel in a common plane permits the buffs as hanging over from the seats 37 from the traveling table to rest at all times upon the stationary table 36. The cutting here 115 may be automatic as in Fig. 1, or manual with manual angular shifting of the seats or shifting without removal of the sections from the seats 37.

In the showing in Fig. 14, seats 39 or 43 120 are provided upon extensible arms 44 mounted in central bearing 45 to be swung over stationary table 46 to be acted upon in a local region by sewing head 2. The sets of plies may be anchored by central pin or seat 125 39 in which instance it is essential that stitching line 48 be not through the center of the set of buff plies. Here the arms as passing the stitching head 2 may have continuity 130 of stitching 48 from one set of plies to an

adjacent set of plies. Such stitching may be severed and the arms swung about with the set of plies given an angular shift for the succeeding stitching line, after swing cutter 47 has automatically cut the stitching 48.

This mechanism is a simple one to permit not only accommodation of different sizes for the buffs as well as different number of arms in use and different radial positions 10 of the stitching through the buffs whether over or short of the center.

These sets of plies of fabric embodying warp and woof are thus built up as sewed into buffer sections. These plies may, as to 15 number, vary, but in practice may run say from eight to twelve to a section. In building up a wheel for operation, it is desirable to take more than one of these sections of plies as assembled into a unit. To meet the 20 condition of high speed of operation the holding down of temperature of the buff is important. There is a great tendency to build up temperature due to high speed of rotation and the friction action upon the 25 material subjected to the buff. This temperature is held down herein by impregnating a ply with stearic acid preferably of a melting point approximating 53° C. In the operation of the buffing wheel this 30 stearic acid tends to melt and disseminate throughout the fabric of the adjacent plies to keep the temperature down.

To speed up the effectiveness of operation of the buffing wheel, an abrading element 35 may be incorporated therewith, and this is accomplished herein by dusting upon the ply as dipped in stearic acid the abrading material, as tripoli, in the form of a dust or powder. Such ply 49 as impregnated with 40 lubricant material herein, preferred as stearic acid, and further adapted as a carrier for abrasive in the form of tripoli, is assembled between adjacent sewed plies, sections or units 50, as an intermediate ply in 45 the buffer wheel. This gives a range for effective operations as may be desired hereunder. In production the manufacturing operations are such as may be effected expeditiously with a continuity of sewing at a 50 maximum advance rate of the sewing head 2 without any delays due to direction change. This means there is produced a uniformity of product with no crowding of the stock for irregularities in thickness of 55 the plies, and that there is a smooth uniform resulting multi-ply fabric stitched assembled section readily adapted to the widest ranges of use by the simple variation in the num-

ber and positioning of the transverse stitching lines.

What is claimed and it is desired to secure by Letters Patent is:—

1. The method of producing multi-ply fabric buffer sections comprising the step of grouping plies in superposed relation, each superposed grouping to form a set, said groupings to provide a plurality of sets; the step of disposing the groupings in a lineally extending series, having an intermediate set in approximately abutting relation with adjacent sets in said series; the step of stitching through one set for securing the plies thereof together, and continuing such stitching in the region of said abutting relation to form stitching connection with said intermediate set, and still further continuing such stitching in the succeeding set in completing such stitching through said series of sets; the step of severing the stitching connecting adjacent sets; the step of shifting a 70 severed stitched set relatively to an adjacent set to obtain a different abutting relation; and the steps of repeating in sequence said stitching, severing and shifting steps, whereby a plurality of sections forming sets of plies receive partial stitching operations thereon in recurring succession.

2. The method of producing multi-ply buffer sections comprising the step of grouping plies in superposed relation, each superposed grouping to form a set, said groupings to provide a plurality of sets; the step of disposing in a lineally extending series, having an intermediate set in approximately abutting relation with adjacent sets in said 90 series; the step of stitching through one set for securing the plies thereof together, and continuing such stitching in the region of said abutting relation to form stitching connection with said intermediate set, and still further continuing such stitching in the succeeding set in completing such stitching through said series of sets; the step of severing the stitching connecting adjacent sets; the step of shifting a 95 severed stitched set angularly upon an axis within itself and relatively to an adjacent set to obtain a different abutting relation; and the steps of repeating in sequence said stitching, severing and shifting steps, whereby a plurality of sections forming sets of plies receive partial stitching operations thereon in recurring 100 succession.

In witness whereof I affix my signature.

HARRY ZIMMERMAN.
